United States Patent Office

Des. 233,381
Patented Oct. 29, 1974

233,381

STOOL

Thomas E. Wright, 1203 Chanticleer Lane,
Hinsdale, Ill. 60521

Filed Mar. 19, 1973, Ser. No. 342,618

Term of patent 14 years

Int. Cl. D6—01

U.S. Cl. D6—29

FIG. 1 is a perspective view of a stool, showing my new design;

FIG. 2 is a view in side elevation of the stool on an enlarged scale;

FIG. 3 is a plan view of the stool as shown in FIG. 2; and

FIG. 4 is a view in rear elevation thereof.

The side of the stool not shown is a mirror image of the side shown.

I claim:

The ornamental design for a stool, substantially as shown and described.
